Bradford C. Gibbs, Cumberland, Md., assignor to
 Celanese Corporation of America, a corporation
 of Delaware

Application May 1, 1935, Serial No. 19,165

8 Claims. (Cl. 8—19)

This invention relates to a method and device for the treatment of women's hosiery, gloves and similar articles that are usually given finishing treatments, while on forms, in baths such as boiling off baths, delustering baths, dye baths, finishing baths, etc.

An object of the invention is a method and device for the economic and expeditious processing, as by finishing treatments that require heated, cooled or chemical baths, of shaped articles, for instance, women's hosiery. Other objects of the invention will appear from the following detailed description and drawings.

In the drawings, wherein like reference numerals refer to the same or similar elements in the various views:

Fig. 1 is an end view of a general plan layout or arrangement of tanks, hoisting mechanisms, racks and work tables.

Fig. 2 is a plan view of the arrangement shown in Fig. 1.

Fig. 3 is a view of a vertical section of a rack for the treatment of women's hosiery.

Fig. 4 is a detailed view of the upper front corner of the rack shown in Fig. 3, parts being in section.

Fig. 5 is a detailed view of one arm of the rack taken on line 5—5 of Fig. 3.

Fig. 6 is an enlarged view of a segment of an arm and corresponds to the plan view shown in Fig. 5.

Fig. 7 is a front view of the rack, a segment of which is shown in Fig. 3.

In prior methods of treating shaped textile articles, such as women's hosiery, etc. in boiling off baths, dye baths and the like, a great amount of space was required and careful regulation of temperature and chemicals was necessary. In the prior methods there were employed long shallow tanks having forms mounted along the edge thereof adapted to be rotated into a horizontal, or treating, position within the tank and up to a vertical position out of the tanks for loading and unloading. Due to the shallowness of the tanks and the great surface area per volume of liquid contained, it was very difficult to regulate temperatures. Due to the long lengths of the tanks employed, it was also very difficult to regulate the even distribution of chemicals such that articles located at various places in the tank would receive the same degree of chemical treatment. When employing heated baths it was necessary for the operators who loaded and unloaded the forms to work almost over the steam tanks and in the vapors emitted from the tanks. By

employing this invention, however, these difficulties are substantially lessened and the operators may perform their work at a distance from the tank, thus adding to their comfort.

Many articles, for instance, hosiery of silk or organic derivatives of cellulose may be reduced to second-grade articles by treatments in baths of improper temperatures or chemical concentrations. By employing a device constructed in accordance with this invention, deep rectangular box-like tanks having a large body of liquid confined in the smallest practical space may be employed. For this reason rapid changes in temperature are not probable and the operator's attention may be employed with other duties than mere regulation of temperatures. The chances of an improper treating temperature are greatly reduced by employing the deep tanks. There is also an economy in floor space when employing heated or cooled baths and economy in the heating or cooling medium employed as there is no large surface, per article treated, exposed to the air. A reduction of about 75 per cent may be made in the floor space required, per article treated, from that formerly employed.

A substantial advantage of employing this invention is that the persons who load and unload the forms may work in comfortable conditions and they are not required to be right at the treating tanks, which was necessary in the former methods. By employing this invention it becomes possible to unload the forms at a distance from the tank and the persons are thus removed from the terrific heat and vapors coming from the surface of the liquid. Further, currents of air may be directed over the persons during the loading and unloading operations without injury to the materials being treated as these currents of air would not contact and change temperatures and chemical concentrations in the treating baths.

In accordance with my invention, I treat articles mounted on forms in liquid baths wherein the forms carrying the articles are submerged in the treating liquid in several horizontal layers, thus increasing the number of articles treated per unit of bath surface exposed. Further, in accordance with my invention I construct a device adapted to contain rows or layers of forms, both vertical and horizontal, adapted to be submerged in baths of substantial depth.

This invention is applicable to the treatment of any textile article which requires immersion in a liquid bath or vapor bath while being held on forms. For instance, this invention may be

employed in the treatment of women's hosiery, men's half hose, gloves, sweaters or other shaped articles made from textile materials or similar materials. The textile material or similar material may be woven, knitted, netted, knotted or otherwise formed from silk, cotton, regenerated cellulose, wool or artificial textile materials containing organic derivatives of cellulose, or mixtures and combinations of these. This invention is particularly applicable to the treatment of women's hosiery made of silk or sized synthetic yarn in that these materials require fairly long treatments in heated baths containing soap or other reagents to remove the natural gums or sizings applied to same. Thus, this invention is of particular importance in the de-gumming of silk hosiery or in the boiling off of sizing from hosiery made of organic derivatives of cellulose which have been treated for knitting purposes with a resin or other size. Textile materials containing organic derivatives of cellulose may include any of the organic derivatives of cellulose, for example, the organic acid esters of cellulose and cellulose ethers. Examples of organic acid esters of cellulose are cellulose acetate, cellulose formate, cellulose propionate and cellulose butyrate, while examples of cellulose ethers are methyl cellulose, ethyl cellulose and benzyl cellulose.

The liquid baths in which the articles are to be treated may be any of the customary baths employed in the finishing of textile materials and may include aqueous or organic baths containing de-gumming agents, size removing agents, scouring soaps, shrinking agents, stitch setting agents, dyes, delustering agents, relustering agents, softening or stiffening agents. These baths may be operated at normal temperatures, reduced temperatures or elevated temperatures. For instance, in the finishing of women's hosiery made of sized yarns containing organic derivatives of cellulose, it is customary to boil the same while on the forms, in aqueous baths containing two to twenty grams of soap per litre for the purpose of removing the size, oils, yarn lubricants, dirt and other materials from the yarns and filaments. Another example of the type of bath that may be employed is in the de-gumming of silk where women's hosiery containing silk in the gum is placed in baths containing enzymes, which baths are maintained at a uniform temperature to develop the activity of the enzymes in digesting the gum from the silk.

The method of this invention in general may be described as the treating of textile articles on forms in liquid baths in such a manner that the liquid employed is confined in as compact a space as is practical and a submerging of the articles on forms in this liquid in such a manner that there may be a plurality of such forms one above the other in the bath. The method also embraces the confining of the liquid in a body such that the surface area thereof is as small as is practicable and the articles are submerged in large numbers at one time.

For the purpose of more fully describing the invention, the same will be described with particular reference to the drawings. In the drawings there is shown a device constructed in accordance with this invention. One general plan is shown in Figs. 1 and 2 where 1 is a suitable tank adapted to contain a liquid. This tank may be provided with heating elements, for example, steam pipes, electric resistance or conductance coils, open flames or other heating ele-

ments, or with cooling means such as coils for the circulation of brine or the like. The tanks may, however, be equipped with both heating and cooling elements to be used alternately or for different types of processes. Although not shown, suitable drains and filling means may be provided. A suitable hoisting mechanism or crane 2, preferably capable of swinging horizontally as well as raising an object vertically, may be provided. Any suitable form of bench or table 3 may be provided to receive and support racks 4 in a position for loading and unloading the forms 19 contained therein.

The device is more fully shown in Figs. 3 to 7 wherein one embodiment of the rack 4 is shown. The racks 4 may consist of a cubicle or rectangular box-like frame 5 formed of angle or L-irons suitably braced on five sides by cross straps 6. Along the lower edge of the unbraced side may be a rod 7 suitably fastened in a bracket or upright member of the frame 5. Near the upper edge, on the same side as the rod 7, there may be downwardly slanting notches 8 formed either in the frame 5, an extension of the cross straps 6 or brackets secured thereto. At the upper corners of the frame 5 may also be placed ears 9 adapted to retain by means of eyes suitable tie chains, or hanging rods 11, that in turn are attached to a grab ring 12 for receiving the hook of the crane or other lifting device. The ears 9 may be formed from an extension of the cross straps 6 or brackets attached thereto.

Threaded on a rod 7 may be collars 13 and hubs 14. The hubs and collars may alternate or may be employed in any order of sequence for the purpose of spacing the hubs or limiting the axial movement thereof when relatively few hubs are used. Formed integral with or attached to each hub 14 is a relatively long flat arm 15. The arms 15 may be made of a flat strip of iron or they may be formed rigidly by employing a suitable length of an angle iron. In the device shown the arms are preferably of a length to reach from the rod 7 to above the bottom of the notch 8 so that they may be held in a vertical position by dropping a fastening rod 16 into the notch 8 behind them.

The arms 15 may have mounted thereon, at spaced intervals along the lower portion thereof, stud shafts 17. Stud shafts 17 may be in the form of bolts as shown in the drawings or they may be cylindrical protuberances formed integral with or welded to the arms. On each of the stud shafts 17 may be mounted a base member 18 adapted to form the base and support for hosiery forms 19 or forms for other similar articles. Each base member 18 may be formed with an extending ear member 21. The ear member 21 may project outwardly at a side and near one end of the base members 18. All extending ears 21, of the base members on one arm, may be connected together with a connecting rod 22. The connecting rod 22 may have attached thereto hand pieces 23. By means of the hand pieces 23 and the connecting rod 22 all the base members 18 along one arm may be rotated simultaneously from a direction parallel to the arm to a direction at substantially a 90° angle to the length thereof. This rotation of the base members permits compact loading of the frame yet when taking off or putting on articles on the frames it provides for ample space for the operator's hands.

For the purpose of making the drawings clear the boil-off shields normally present on the forms 75

have been omitted from the drawings. Any suitable type of boil-off shield may be employed. However, I prefer to use the one shown in my co-pending application S. No. 11,519 filed March 3, 5 1935. These shields may be pivoted to the base members 18 by suitable projecting pins as fully disclosed in the above co-pending application. According to the user's taste, these shields may be caused to be tipped in unison away from the 10 hosiery form by connecting all the shields along one arm to a single connecting rod which may be pulled downwardly or pushed up to swing all shields in unison.

In operation, a rack 4 is deposited upon table 15 or bench 3 which preferably consists of two parallel uprights and the rod 16 is removed from the rack. One arm from the rack is swung to a horizontal position and by means of the hand pieces 23 the forms are rotated to substantially 20 a 90° angle to the length of the arm. The forms while in this position are loaded with hosiery, say, from one to eight or more pieces to each form. Then, by means of the hand pieces 23 the forms are rotated back to a position substantially parallel to the arm and the arm swung to a vertical position. In like manner each arm may be loaded, after which the rod 16 may be inserted 25 back of the vertically positioned arms to lock the same in that position.

30 The tank 1 is filled with a suitable liquid and adjusted to the proper temperature. The rack 4 is then hoisted by the crane from the table 3 and moved to a position over the tank. The rack is then lowered into the tank while the hoist 35 picks up the rack previously placed in the tank from the tank containing the treated articles and moves it to the table where the rack is stripped of the articles contained therein and the same is again loaded in the manner described above.

40 In the boiling off of the sizing from hosiery formed of organic derivatives of cellulose approximately fifteen minutes are required to load the frame shown in the drawings, after which it is placed in the boiling off vat by means of an electric crane. The second frame is loaded and placed in the boil off. At the end of forty minutes from the start the first frame has been sufficiently 45 treated and is ready to be removed. As soon as this frame is removed the third frame which has been loaded is lowered into the vat and the one just removed is unloaded and reloaded. This unloading and reloading requires a period of approximately twenty minutes, at the end of which time the second frame is ready to be removed and 50 the reloaded frame placed in the tank in its stead.

55 The above description and drawings are given merely by way of illustration and many modifications may be made therein without departing from the spirit of my invention.

60 Having described my invention, what I desire to secure by Letters Patent is:

1. Apparatus for the treatment of textile articles with a liquid medium, comprising a box-like frame, a plurality of arms pivotally connect- 65 ed to said frame, and forms, upon which the tex-

tile articles are adapted to be positioned for treatment, supported on said arms.

2. Apparatus for the treatment of textile articles with a liquid medium, comprising a box-like frame, a plurality of arms pivotally connected to said frame, and forms, upon which the textile articles are adapted to be positioned for treatment, supported on said arms, said forms being horizontally arranged when the apparatus is in operative position for the treatment with the 10 liquid medium. 5

3. Apparatus for the treatment of textile articles with a liquid medium, comprising a box-like frame, one side of said frame comprising a plurality of hinged arms, and forms, upon which 15 the textile articles are adapted to be positioned for treatment, mounted on said arms in spaced, non-touching relation.

4. Apparatus for the treatment of textile articles with a liquid medium, comprising a box- 20 like frame, one side of said frame comprising a plurality of hinged arms, and forms, upon which the textile articles are adapted to be positioned for treatment, mounted on said arms in spaced, 25 non-touching relation, said forms being horizontally arranged when the apparatus is in operative position for the treatment with the liquid medium. 25

5. Apparatus for the treatment of textile articles with a liquid medium comprising a box-like frame, a plurality of arms pivotally connected to said frame, forms, upon which the textile articles are adapted to be positioned for treatment, supported on said arms and means for rotating 30 said forms relative to said arms. 35

6. Apparatus for the treatment of textile articles with a liquid medium comprising a box-like frame, a plurality of arms pivotally connected to said frame, forms, upon which the textile articles are adapted to be positioned for treatment, 40 supported on said arms and means on each arm for simultaneously rotating the forms supported thereon. 40

7. Apparatus for the treatment of textile articles with a liquid medium, comprising a box- 45 like frame, a plurality of arms pivotally connected to said frame, base members mounted on said arms, forms, upon which the textile articles are adapted to be positioned for treatment, supported by said base members and means for rotating said base members, whereby the forms are rotated relative to said arms. 50

8. Apparatus for the treatment of textile articles with a liquid medium, comprising a box-like frame, a plurality of arms pivotally connect- 55 ed to said frame, base members mounted on said arms, forms, upon which the textile articles are adapted to be positioned for treatment, supported by said base members and means on each of said arms for simultaneously rotating the base 60 members mounted thereon whereby the forms are simultaneously rotated relative to the arm upon which they are supported. 60

BRADFORD C. GIBBS.
